the United States Atomic Energy Commission

Application March 13, 1950, Serial No. 149,313

19 Claims. (Cl. 315—62)

1

This invention relates to arc gaps and more particularly to those suitable for passing heavy currents and at a definite and constant breakdown potential also known in the art as low-jitter time. For specific applications such as the supplying of energizing potential to the deflector plates of synchro-cyclotrons, there is required also an arc gap having high trigger-pulse impedance but low arc impedance and the present invention is well suited for usage when such special requirements are present. To more general circuit applications, moreover, in which a heavy-duty arc gap is desirable, as for supplying substantially instantaneously electrical current to a heating load, the invention is equally well adapted.

Accordingly, it is an object of the invention to provide a new and improved arc gap construction capable of passing a heavy current substantially instantaneously.

A second object is to provide a new and improved arc gap unit containing a saturable reactor integrally disposed therein.

A further object is to provide a reactor type arc gap providing an especially short current path between the reactor and the gap.

Another object is to provide in a reactor type arc gap, means for ionizing the intervening gap space.

Another object is to provide a compact, heavy duty arc-gap unit having an integrally contained cooling system therein.

Still another object is to provide an improved power control circuit incorporating a saturable core triggered arc gap.

A further object is to provide an improved combination of triggered arc gap means and a triggering circuit therefor.

A still further object is to provide an improved combination of triggered arc gap means and a power circuit controlled thereby.

Other objects and advantages of the invention will become apparent as the description proceeds and when considered in conjunction with the accompanying drawing in which

Figure 1 is a partial sectional view of a preferred form of arc gap unit embodying the invention, and

Fig. 2 is a diagrammatic view of a power control circuit including an arc gap unit of the type shown in Figure 1.

As is known, the use of heavy surges of power may impose demands upon power circuits for which the well-known and normally effective "Thyatron" equipment is inadequate. In one particular application of the present invention a

2

current of the order of 7000 amperes and at a potential of 15 kv. was required to be delivered to a load for a time of about 0.1 microsecond. In order to meet such demands it is apparent that the gap means for periodically applying this power surge must be capable of repeated, heavy-duty use, must have adequate provision for dissipating heat and must possess mechanical strength.

With these requirements in mind, reference is now made to Fig. 1 which shows a base plate 10 which may be supported at any desired stationary location and has preferably the form of a disc centrally apertured at 11. Seated on the upper face of plate 10 and concentric with aperture 11 is an electrode-carrying, inner cylinder 12 having a conical closure at its upper end and whose lateral wall forms a continuation of the wall of aperture 11. Surrounding the cylinder 12 and in spaced, concentric relation thereto is an outer cylinder 14 also seated on the base plate 10 and defining with said inner cylinder 12 and plate 10 a ring-shaped chamber of substantial longitudinal extent. The bottom, top and side walls of such chamber are lined with layers 5 of porous, insulating material, such as glass wool or the like, which serves to space and insulate from the chamber walls a stack of rectangularly cross-sectioned annular rings 13 preferably of highly permeable magnetic material, such as Permaloy. Layers 6 of insulating material corresponding in outline to the vertical projection of the rings 13 serve to space the latter from each other and to effectively occupy, together with the rings 13, the space within said chamber.

For dissipating the heat generated within the structure thus far described, inner cylinder 12 is provided with an aperture 15 extending laterally through the wall thereof and at a point just below its upper closure. A similar aperture 16 extends through the lower portion of the cylinder wall above the plate 10. Apertures 15 and 16 serve as passageways for conducting a suitable insulating oil to the interior of cylinder 12 whose lower end bounded by the wall of aperture 11 is closed by an expansible means such as convoluted bellows 17 which fills the major portion of the space within inner cylinder 12. As will be apparent from Fig. 1, oil may be supplied from an extension pipe 18, through suitable flow control means such as cock 19 to an inlet pipe 20 which projects through outer cylinder 14 to convey oil through layers 5 and 6 of insulating material and thence through apertures 15, 16 to the interior of the inner cylinder 12. After filling has been accomplished cock 19 is closed, the bellows 17 serving

to maintain oil throughout the system irrespective of temperature variations caused by operation of the gap structure and also to radiate heat to the exterior of the structure by means of the exposed outer surface of the bellows. Heat dissipation from the exterior wall of outer cylinder 14 is further facilitated through the provision of a tubular conduit 21 whose spaced turns are united in heat transfer relation to the cylinder wall and whose interior may be filled with a circulated, suitable coolant.

The gap structure proper is disposed above the cooling arrangement which has been described and comprises a pair of massive terminals 33, 36 of generally disc-like conformation arranged in axial symmetry and separated by a space indicated at 37. Lower terminal 33 is provided with a central stud 38 which threadedly engages a bore provided in an upper reduced extension 39 of inner cylinder 12.

Surrounding the upper end of outer cylinder 14 in telescoping relation and to which it is united as by peripheral welding indicated at 40 is a rigid collar 41 of considerable wall thickness and which serves as intermediate supporting means for the upper terminal 33, electrical connections and gap enclosure or arc chamber 42. The latter is defined by a circular plate 43 having a central opening closely fitting the upper end of collar 41 and suitably welded thereto, an annular ring 44 of suitable high dielectric material such as "Lucite" and a cover plate and upper terminal support 45. Preferably, the oppositely disposed faces of plates 43 and 45 are circumferentially recessed inwardly of their peripheries to provide seats for insulating ring 44 which is maintained in fixed relation between said plates by suitably recessed means, such as the spaced screws 46. Upper terminal 36 is provided with a central stud 38 which is threaded into a cooperating threaded bore disposed centrally of upper plate 45 and in axial coincidence with stud 38 as will readily be apparent from the drawing.

To exclude oil from the layers 6 of porous insulating material from arc chamber 42, a ring 47 of compressible, insulating material is snugly fitted in sealing relation between the inner wall of collar 41 and reduced extension 39 and overlying the stack of rings 13 and layers 6. An annular plate 48 is provided with a threaded central aperture for engagement with the similarly threaded upper end of extension 39 and is disposed thereby to press ring 47 downwardly to accomplish an effective seal. By making the portion of ring 47 engaged by plate 48 of greater axial thickness than the remainder of such ring, as shown, it will be apparent that effective sealing action will be exerted laterally against the inner wall of collar 41, also.

The mechanical aspects of my improved gap structure having been described, consideration will now be given to the immediate electrical connections thereof and later to their energization. A suitable coaxial cable 53 which is preferably securely attached to the plate 43 in any suitable manner includes a central conductor 49 electrically connected to the side of terminal 33 and a suitable outer conductor 50. Since the collar 41, outer cylinder 14, plate 43 and inner cylinder 12, as well as the gap terminals 33, 36, are made of electrically conducting, but non-magnetic material such as brass, it will be apparent that upon applying a suitable source of potential across the outer terminals of coaxial cable 53, a path of current flow will exist along the electrically con-

ducting elements named with resultant magnetization of rings 13. For providing improved ionization in the arc chamber 42, the wall of collar 41 opposite from cable 53 has sealingly mounted therein a short length of resistance type coaxial cable having an outer end shorted at 51. At the opposite end 52 of this cable the central resistance element is pointed and disposed adjacent but spaced from the side of gap terminal 33 as shown in Fig. 1. Upon the application of a suitable potential to gap terminal 33, in a manner later to be described, a corona discharge will take place between the terminal 33 and the pointed conductor 52 and initiate ionization in the arc chamber 42.

Specific utilization of the arc gap as described in the foregoing, in the application of a high current at high voltage to the ion deflector of a synchro-cyclotron will now be detailed. As shown in Fig. 2, a suitable D. C. power supply 55 having a grounded, negative terminal and a positive terminal in series with a one milli-henry choke 56 connected to the central conductor 49 of the coaxial cable 53 causes a flow of current around the stack of magnetic rings 13 biasing them to as near saturation as desired. A D. C. power supply 57 having its negative terminal likewise grounded and its positive terminal connected to the plate of a diode 58 serves to charge a 15 kilovolt capacitor 59 which is connected to the remaining element of diode 53. A gas filled triode 60 having its plate connected to the same side of capacitor 59 as diode 53 and its cathode grounded is provided with terminals 61, 62 which are connected to the grid and cathode, respectively, of said triode. A positive, triggered pulse may be applied to said terminals to render triode 60 conductive, discharging capacitor 59 and sending a positive pulse over coaxial cable 53, which due to the inductive reactance of magnetic rings 13, causes a voltage differential to exist between lower arc terminal 33 and outer cylinder 14. This voltage differential is sufficient, with the aid of the pointed end 52 of the shorted coaxial cable (Fig. 1) to ionize the space between the upper and lower electrodes 36 and 33 sufficiently to permit initiation of the arc current therebetween at about a current density of 7000 amperes and at a voltage of about 15 kilovolts.

The arc discharge thus initiated is maintained by a power source including an adjustable D. C. power supply 67 having a range of from one to ten kilovolts and having its positive terminal connected to the plate of a charging diode 68 and with its negative terminal grounded. The cathode of diode 68 is connected in series with a charging inductance 69 which in turn is connected to charge a bank of capacitors 71 (shown as a single capacitor) and also connected in any suitable manner to the upper arc terminal plate 45 as indicated in Fig. 2. The charging circuit of capacitors 71 is completed by connecting the opposite terminal thereof in series with the primary winding 72 of a deflector transformer 73 and thence to the lower arc chamber plate 43, which like the negative terminal of power supply 67 is connected to ground. The secondary winding 74 of transformer 73 is adapted to be connected to the deflector plates of the synchro-cyclotron previously referred to for effecting the removal of the charged particles.

It will be apparent from the description immediately preceding, that the high current flow of the initiated discharge will saturate the already partly saturated magnetic rings 13 and reduce to

at low value the impedance path permitting a rapid discharge of capacitor bank 71 through primary winding 72 and across arc terminals 33, 36. Through proper selection of values for the inductance 69 and bank of capacitors 71, it will be seen that the voltage impressed on the primary winding 72 may be double that supplied by the power supply 67.

While I have described the salient features of this invention in detail with respect to one embodiment, it will of course be apparent that numerous modifications may be made within the scope of this invention, and I do not therefore desire to limit the invention to the exact details shown except insofar as they may be defined in the following claims.

What is claimed is:

1. A heavy duty arc gap comprising a pair of spaced plates interconnected by an insulating arcuate wall and defining an arc chamber, a gap terminal carried by one of said plates and extending into said chamber, an opposing gap terminal supported by the other of said plates, and means including magnetically saturable conductive elements series connected to one of said terminals for providing high trigger pulse impedance but low arc impedance to said gap.

2. The combination set forth in claim 1 wherein in a pointed resistance type conductor is disposed in spaced relation to the latter gap terminal and electrically connected to its supporting plate for ionizing the gas within said arc chamber.

3. The combination set forth in claim 1 wherein in a coaxial cable having its central conductor connected to the latter gap terminal and its outer conductor connected to its supporting plate serves to energize said gap and the pointed central element of a terminally shorted, resistance type, coaxial cable having its outer conductor electrically connected to said plate serves to ionize the gas within said arc chamber.

4. A heavy duty arc gap comprising a pair of spaced plates interconnected by an insulating, arcuate wall and defining an arc chamber, a gap terminal carried by one of said plates and extending into said chamber, an opposing gap terminal supported by the other of said plates, and additional supporting means disposed intermediate the latter gap terminal and its supporting plate including a cylindrical conductive element connected to said terminal and a magnetically saturable core disposed adjacent said element for providing high trigger pulse impedance but low arc impedance to said gap.

5. A heavy duty arc gap comprising a pair of spaced plates interconnected by an insulating, arcuate wall and defining an arc chamber, a gap terminal carried by one of said plates and extending into said chamber, an opposing gap terminal supported by the other of said plates, a pair of spaced, coaxial and conducting cylinders disposed between the latter terminal and its supporting plate, and a plurality of magnetically saturable rings disposed between said cylinders for providing high trigger pulse impedance but low arc impedance to said gap.

6. A heavy duty arc gap comprising a pair of spaced plates interconnected by an insulating, arcuate wall and defining an arc chamber, a gap terminal carried by one of said plates and extending into said chamber, an opposing gap terminal supported by the other of said plates, a pair of spaced, coaxial and conducting cylinders disposed between the latter terminal and its supporting plate, and a plurality of magnetically

saturable rings disposed between said cylinders and separated therefrom and from each other by a layer of porous, insulating material for providing high trigger pulse impedance but low arc impedance to said gap.

7. A heavy duty arc gap comprising a pair of spaced plates interconnected by an insulating, arcuate wall and defining an arc chamber, a gap terminal carried by one of said plates and extending into said chamber, an opposing gap terminal supported by the other of said plates, a pair of spaced, coaxial and conducting cylinders disposed between the latter terminal and its supporting plate, a closure at each end of said cylinders for providing a fluid-tight compartment between the latter, a plurality of magnetically saturable rings disposed in said compartment, separated from said cylinders and from each other by a layer of porous, insulating material and means for supplying a cooling and insulating fluid to said layer.

8. A heavy duty arc gap comprising a pair of spaced plates interconnected by an insulating, arcuate wall and defining an arc chamber, a gap terminal carried by one of said plates and extending into said chamber, an opposing gap terminal supported by the other of said plates, a pair of spaced, coaxial and conducting cylinders disposed between the latter terminal and its supporting plate, a closure at each end of said cylinders for providing a fluid-tight compartment between the latter, and for closing the separate compartment within said inner cylinder, a plurality of magnetically saturable rings disposed in said first compartment, separated from said cylinders and from each other by a layer of porous, insulating material, the inner one of said cylinders being provided with axially spaced perforations for the circulation between said compartments of a cooling and insulating fluid supplied to said first compartment.

9. The combination set forth in claim 8 wherein in an expansible, corrugated bellows is disposed in said second compartment with its outer surface serving as a closure for said inner cylinder and effective to vary the volume of fluid in the latter in response to variations in the temperature of said fluid.

10. The combination set forth in claim 8 wherein one of said closures is formed of resilient, insulating material for ensuring compact disposition of said insulated rings within said first compartment.

11. A heavy duty arc gap comprising a circular plate having a gap terminal mounted centrally thereof, a composite, inwardly stepped, cylindrical member having a flange portion, an insulating arcuate wall joining said flange portion and the periphery of said plate to define an arc chamber, an inner cylinder disposed coaxially of said member and having a closed end proximate to the stepped portion of said member, an opposing gap terminal mounted in said closed end, an annular base plate united in fluid-tight relation to the opposite end of said cylinder and said member, a plurality of magnetically saturable rings disposed between said cylinder and said member and a resilient ring overlying said first rings and maintained in position by said opposed gap terminal for ensuring compact disposition of said first rings.

12. The combination set forth in claim 11 wherein an annular ring of rigid material is disposed in threaded relation on said inner cylinder and between said opposed terminal and said re-

silent ring for transmitting pressure from the former to the latter.

13. In combination a heavy duty arc gap comprising a pair of spaced plates interconnected by an insulating arcuate wall and defining an arc chamber, a gap terminal carried by one of said plates and extending into said chamber, an opposing gap terminal supported by the other of said plates, means including magnetically saturable conductive elements and a source of magnetizing current series connected to one of said terminals, a condenser connected to said source, means for charging said condenser and means for discharging said condenser across said gap terminals for initiating an arc discharge in said arc chamber.

14. In combination a heavy duty arc gap comprising a pair of spaced plates interconnected by an insulating arcuate wall and defining an arc chamber, a gap terminal carried by one of said plates and extending into said chamber, an opposing gap terminal supported by the other of said plates, a resistance-type conductor having one end connected to said other plate and having its other end pointed and terminating in spaced relation to said opposing gap terminal, means including magnetically saturable conductive elements and a source of magnetizing current series connected to one of said terminals, a condenser connected to said source, means for

30

charging said condenser and means for discharging said condenser across said gap terminals for initiating an arc discharge in said arc chamber.

15. The combination set forth in claim 14 wherein said first source comprises a D. C. power supply and series connected choke.

16. The combination set forth in claim 14 wherein said first source comprises a D. C. power supply and series connected choke and said condenser charging means comprises a D. C. power supply and a series connected charging diode.

17. The combination set forth in claim 14 wherein said first source comprises a D. C. power supply and series connected choke and said condenser discharging means comprises a pulse triggered triode.

18. The combination set forth in claim 14 and including a condenser connected across said gap terminals, and means for charging said condenser.

19. The combination set forth in claim 14 and including a condenser and the primary winding of a deflector transformer connected in series across said gap terminals and means including an adjustable D. C. power supply and series connected charging diode and inductance for charging said last named condenser.

QUENTIN A. KERNS.
